UNITED STATES PATENT OFFICE.

WILLIAM M. DUNCAN, OF ALTON, ILLINOIS.

FURNACE.

Application filed February 1, 1922. Serial No. 533,471.

This invention relates to improvements in furnaces, and more particularly to a furnace provided with draft boxes surrounded by a traveling grate, the main object being to provide a simple means for removing ashes from the draft boxes which lie below the fuel-supporting portion of the grate.

In the preferred form of the invention, each draft box is open at the top for the discharge of draft through the fuel-supporting portion of the grate, and this allows the ashes, together with the fine particles of fuel, to drop into the draft box. As a means for removing the ashes from the draft box, I preferably provide said draft box with an inclined bottom portion having an opening for the egress of ashes, said opening being normally closed by a closure which may be opened by certain mechanism, the operating portion of which extends outside of the furnace, whereby said ashes are permitted to fall by gravity to the lower course of the traveling grate through which they pass.

Another object is to provide an ash discharge means adapted to be carried by a portable mechanical stoker, having detachable elements allowing the portable stoker to be moved into and out of the furnace.

Fig. I is a longitudinal section, illustrating a mechanical stoker embodying the features of this invention, the middle portion of the apparatus being broken away.

Fig. II is a transverse section on the line II-II, of Fig. I.

Fig. III is an enlarged fragmentary section showing the lower portion of a draft box, the closure being shown in place closing the opening therein, and a portion of the mechanism for retaining said closure in such position being shown.

Fig. IV is a fragmentary view showing the sealing strip for preventing leakage of draft around the closure when said closure is in place closing the ash outlet.

Fig. V is a fragmentary section showing a modified form of the invention wherein the ash opening, instead of being at an angle to the top edge of the draft box, as in the preferred construction, is parallel therewith.

To illustrate the invention, I have shown a mechanical stoker comprising an endless chain grate A supported between side frame members 1 mounted on wheels 2. The chain grate comprises many grate links 3 connect-

ed by means of pivot rods 4 arranged transversely of the grate. A power shaft 5 (Fig. I), supported by the side frames 1, is provided with any desired number of sprocket wheels 6 for transmitting movement to the endless chain grate. The chain grate passes around the sprocket wheels 6 and also around a plain idle wheel, or roll 7, the latter being mounted on a shaft 8. The fuel passes from a hopper 9 to the top face of the grate, as indicated by arrows in Fig. I.

The furnace is provided with suitable side walls B and B', including refractory members 10 located adjacent to the side margins of the grate. The lower portion of the side wall B' is hollow, as shown in Fig. II, to provide an inlet passageway 11 for the draft. 12 designates draft boxes surrounded by the traveling grate and extending from one side frame 1 at one side of the grate to the side frame 1 at the other side thereof. All of these boxes are open at the top to provide for the delivery of the draft to the grate, and are provided with vertical side walls in the form of flanged beams.

One end of each draft box is provided with an intake nipple 13 for the admission of draft. Since the grate is supported by a portable frame, including the side frame members 1 adapted to be moved into and out of the furnace, the nipples 13 are detachable, each nipple being telescoped with one of the side frame members 1 and also with one of the furnace walls.

Each draft box 12 is provided with an inclined bottom, said inclined bottom being produced by a V-shaped bottom member 14 which is secured, at its upper edges, to the opposite side members of said draft box. Formed in each of the V-shaped bottom members 14 is an ash discharge opening 15, extending longitudinally of said draft box, said ash discharge opening terminating just short of the side frame members 1. It will be noted by referring to Fig. I of the drawing that a portion of the ash discharge opening 15 is located at the lowermost point of the inclined bottom of each draft box, and as a result thereof all of the ashes, and every small particle of fuel which drops into a draft box, will be conveyed by the inclined bottom walls of said draft box to said ash discharge opening.

Extending longitudinally of each draft box 12 is a shaft 16 rockably supported in bearings 17 formed on one of the inclined

portions of the V-shaped bottom 14. One end portion of said shaft extends through one of the side frame members 1 and is provided with a non-circular end adapted to 5 receive a suitable coupling which connects said shaft 16 to operating mechanism which will be hereinafter set forth.

Mounted on each of the shafts 16, and adapted to swing independently thereof, is a 10 closure 18, adapted to close the ash discharge opening 15 in the draft box 12. Each of said closures preferably comprises a casting overlapping the margins of the opening 15 and being provided with a plurality of lugs 15 19, each of which is provided with a yoked end adapted to embrace the shaft 16. To prevent the lugs 19 from being displaced from the shaft 16, a bolt 20 is passed through the projecting legs 19' of said lugs (Fig. 20 III).

Since the successful operation of a furnace of the class described herein depends upon efficient means for controlling the flow of air to or from the endless chain grate, it is important to close the draft boxes in such a 25 manner that the draft will not be materially affected by leakage, hence a tight joint is necessary between the closures 18 and those portions of the draft boxes adjacent to the 30 ash discharge openings 15. A tight joint between the parts mentioned could be obtained by carefully machining the meeting faces of said parts, but this is a rather expensive operation and much of it is dispensed 35 with by the use of parts which will now be described.

Secured to one of the inclined portions of each of the V-shaped bottom members 14 is an adjustable sealing plate 21, said sealing 40 plate being provided with a plurality of elongated slots 22, each of which is adapted to receive a bolt 23 which passes through an opening in said inclined wall of the V-shaped bottom and through said elongated slot, 45 whereby said sealing plate is adjustably held in place. To adjust the sealing plate relative to said V-shaped bottom, it is apparent that it is only necessary to loosen the bolt 23, after which said sealing plate may be moved 50 freely toward or away from the closure 18 to locate said sealing plate in the desired position, where it may be fixed by again tightening said bolt 23. The particular advantage of using the sealing plate 21, aside from 55 its adjustability, lies in the fact that to obtain a tight joint between the closure and the V-shaped bottom of the draft box it is only necessary to machine the lower edge of the comparatively narrow plate 21, and that narrow portion of the closure which contacts 60 with said sealing plate, while if said plate were not used all of the meeting faces of said closure and said V-shaped bottom would have to be machined. The adjustability of the 65 sealing plate, of course, permits manipula-

tion thereof to obtain a tight joint between the closure and the V-shaped bottom of the draft box.

Mounted on each of the rockable shafts 16 is a plurality of dogs 24, each of which 70 comprises a hub portion which surrounds said shaft 16 and is fixed thereto by means of a key shown in Fig. II, and a closure-engaging portion 24'. Each closure 18, as has already been stated, is loosely mounted on the shaft 16, and the closure contacting portions 24' of the dogs 24 contact with said closure at points which are approximately midway between the upper and lower edges of said closure. Hence, if the shaft 16 were 75 rocked in a direction to force the closure contacting portions of the dogs 24 against the closure, said closure would be forced tightly against the V-shaped bottom of the draft box, and because the pressure is applied directly against said closure at points 80 equidistant from the upper and lower edges of the closure, said pressure will be equally distributed along said edges of said closure and a tight joint will result.

Each of the shafts 16 is provided at one of its ends with a non-circular portion 16', which is adapted to receive a coupling 25 having a non-circular opening for the reception of said non-circular end, the end of 95 said coupling opposite to the end that engages the shaft 16 being secured by means of a bolt to an operating shaft 26. The shaft 26, as will be observed by referring to Fig. II of the drawing, extends across the inlet passageway 11 and through the portions 100 of the furnace wall B' on either side of said passageway. Imbedded in the outer portion of the furnace wall B', at the point where the operating shaft 26 extends 105 through said wall portion, is a hollow casting 27 having a reduced portion 27' on its inner face, the purpose of which will be subsequently pointed out.

Supported by the lower portion of each 110 hollow casting 27 is a bearing 28, in which one of the operating shafts 26 is journaled, said bearing being secured to said hollow casting by means of suitable bolts or other fastening means, and is provided with a 115 rigid toothed segment 29. An operating lever 30 is fixed to the outer end of each operating shaft 26, said lever being provided with a pivoted pawl 31 which engages the toothed face of the segment 29. From the foregoing it is apparent that if the operating lever were moved, the pawl 30 would engage successive teeth on the segment 29 whereby said operating lever 30 would be 120 retained in various positions relative to said segment.

To prevent the air within the air passage- 125 way 11 from escaping through the furnace wall around the operating shafts 26, I employ a tube 32 which surrounds the shaft 130

26, one end of said tube being secured within the reduced portion 27' of the hollow casting 27 and the other end thereof being extended through the inner portion of the furnace wall B' whereby the escape of air around said shaft is prevented.

In use, the closures 18 of my furnace are normally closed, in which position the operating levers 30 are in the position in 10 which they are shown in Fig. I of the drawing with the nose of the pawl 31 being engaged by one of the teeth on the toothed face of the segment 29. In the event it is desired to remove the closure 18 from the 15 ash discharge opening 15 to permit the ashes to be discharged therethrough, the extension 31' on the pawl 31 is depressed, which will cause said pawl to swing on its pivot, thereby disengaging the nose thereof from 20 the tooth on the segment 29 and permitting said operating lever to be moved in the direction indicated by the feathered arrow in Fig. I, which movement will cause the closure-engaging portions 24' of the dogs 24 to move away from said closure and permit 25 same to swing by gravity away from the ash discharge opening.

Upon the removal of the closures 18 from the ash discharge openings 15 in the manner just described, the ashes within the draft boxes will, of course, drop by gravity through said openings, and will fall onto the lower course of the traveling grate A. The links 3 of the grate A are located comparatively close to each other in a lateral direction, hence nothing but the smaller particles of ashes would be permitted to pass through said traveling grate until said ashes had been carried to the point indicated by the reference character A' in Fig. I, at which point said grate links, due to the fact that the grate A is curved by being passed over the sprocket wheels 6, draw away from each other leaving spaces therebetween, and the ashes will pass through these spaces between said links and fall by gravity to the space under said grate.

When it is desired to remove the portable stoker from the furnace, the operating lever 30 and the operating shaft 26 are drawn outwardly, thereby disengaging the coupling 25 from the non-circular end 16' of the shaft 18.

In the modification shown in Fig. V, a 55 horizontal closure 18' is shown. In this form of the invention, a pair of adjustable sealing plates 21' is used. The operation of the mechanism shown in Fig. V is the same as the operation of the similar mechanism shown in the preferred construction.

I claim:

1. A furnace provided with an endless traveling grate, a draft box surrounded by said grate, said draft box being open at the 60 top for the discharge of draft through the

fuel-supporting portion of the grate and having an ash discharge opening for the removal of ashes therefrom, said draft box being provided with inclined bottom portions leading to said ash discharge opening, 70 a closure, a rockable shaft on which said closure is loosely pivoted, and members fixed to said rockable shaft and contacting with said closure whereby same may be moved to a position to close said ash discharge opening. 75

2. A furnace provided with an endless traveling grate, a draft box surrounded by said grate, said draft box being open at the top for the discharge of draft through the fuel-supporting portion of the grate and 80 having an ash discharge opening for the removal of ashes therefrom, said draft box being provided with inclined bottom portions leading to said ash discharge opening, 85 a closure, a rockable shaft on which said closure is loosely pivoted, members fixed to said rockable shaft and contacting with said closure whereby same may be moved to a position to close said ash discharge opening, 90 and means whereby said rockable shaft may be rocked.

3. A furnace provided with an endless traveling grate, a draft box surrounded by said grate, said draft box being open at the top for the discharge of draft through the fuel-supporting portion of the grate, and having an ash discharge opening for the removal of ashes therefrom, said draft box being provided with inclined bottom portions leading to said ash discharge opening, 100 a closure, a rockable shaft on which said closure is loosely mounted, dogs fixed to said rockable shaft and contacting with said closure whereby same may be moved to a position to close said ash discharge opening, 105 means extending outside of said furnace whereby said rockable shaft may be rocked, and means including a ratchet and pawl whereby said closure may be locked in a closed position. 110

4. A furnace provided with an endless grate, a draft box surrounded by said grate, said draft box being open at the top for the discharge of draft through the fuel-supporting portion of the grate, said draft box being provided with an ash discharge opening whereby the ashes which drop into said draft box may be removed therefrom, a closure for said ash discharge opening, and means comprising an adjustable sealing 115 plate whereby a tight joint between said closure and said draft box is obtained.

5. A furnace provided with an endless grate, a draft box surrounded by said grate, said draft box being open at the top for the discharge of draft through the fuel-supporting portion of the grate and having an ash discharge opening for the removal of ashes therefrom, said draft box also being provided with inclined bottom portions leading 120 125 130 135

4
to said ash discharge opening, a closure for said ash discharge opening, a sealing plate whereby a tight joint between said closure and said draft box is obtained, said sealing plate being provided with elongated slots, and fastening devices extending through said slots to adjustably secure said sealing plate to said draft box.

6. A furnace provided with an endless grate, a draft box surrounded by said grate, said draft box being open at the top for the discharge of draft through the fuel-supporting portion of the grate, and having an ash discharge opening for the removal of ashes therefrom, said draft box being provided with inclined bottom portions leading to said

ash discharge opening, a closure, an adjustable sealing plate whereby a tight joint between said closure and said draft box is obtained, a rockable shaft on which said closure is loosely mounted, dogs fixed to said rockable shaft and contacting with said closure whereby same may be moved to a position to close said ash discharge opening, operating means extending outside of said furnace whereby said rockable shaft is rocked, and a ratchet and pawl whereby said closure may be locked in a closed position. 20 25

In testimony that I claim the foregoing I hereunto affix my signature.

WILLIAM M. DUNCAN.
